UNITED STATES PATENT OFFICE.

JOHN J. BERRIGAN, OF ORANGE, NEW JERSEY.

CENTRIFUGAL SEPARATOR.

965,558.

Specification of Letters Patent. Patented July 26, 1910.

Application filed November 7, 1905. Serial No. 286,193.

To all whom it may concern:

Be it known that I, JOHN J. BERRIGAN, of Orange, Essex county, New Jersey, have invented a new and useful Improvement in Centrifugal Separators, of which the following is a specification.

The invention relates to centrifugal separators for solids and liquids.

The principle of the invention consists in subjecting the combined solids and liquids to separation in order to remove the greater part of the liquid, then conveying the residual solid with such liquid as may remain therein through a series of frusto-conical chambers disposed in a rotary cylinder and axially concentric therewith, in each of which chambers the materials are first projected outwardly, centrifugally toward or to the wall of said cylinder, and then moved centrifugally to the central outlet leading to the next chamber. The liquid may escape from each chamber by an independent outlet therein, and the solid material is dried by being carried by the conveying scrapers 25 around the inner surface of the chamber and toward its axis, as well as onward to the delivery outlet of the last chamber.

The invention consists in the construction hereinafter set forth which embodies said principle and in the particular combinations recited in the claims.

In the accompanying drawings—Figure 1 is a vertical longitudinal section of the machine. Fig. 2 is a cross section on the line 35 $x-x$ of Fig. 1. Fig. 3 is an elevation of the delivery end of the machine.

Similar numbers and letters of reference indicate like parts.

1 is a horizontal cylinder within which the working parts of the machine are inclosed. On the head 2 of said cylinder is a hollow trunnion received in a bearing in the fixed standard 3. Bolted to the opposite head 4 of said cylinder is a cylindrical casing 5, on which is formed a hollow trunnion which is received in a bearing in the fixed standard 6. Standards 3 and 6 rest upon the bed 7 of the machine. The driving pulley 8 is fast upon the cylinder trunnion. Power is communicated to said pulley by any suitable belt (not shown) and in that way cylinder 1 is caused to rotate.

It is the feed hopper supported on bracket 10, extending from standard 3.

55 The combined solid and liquid materials to be separated are conveyed into the cylin-

der 1 by means of a screw conveyor 11, the shaft of which is supported at one end in a bearing on the bracket 10 and carries the sprocket wheel 12. The other end of said conveyor shaft is stepped in a wall of a chamber 13 formed upon the inside of the head 2 which chamber by means of the inclined duct 14 communicates with the interior of cylinder 1.

Passing through the hollow trunnion and entering the casing 5 is a shaft 15 which is held in stationary position by a lever arm 17, fast on the outer end of said shaft, which lever arm is connected by a rod 16 with the bed of the machine. Any other convenient means may be used for holding said shaft stationary. Within the casing 5, the shaft 15 carries the toothed gear 17, and, engaging with said gear 17, is a pinion 18, the shaft of which is journaled in the head 4 of the cylinder and in the head 19 of casing 5. Said pinion also engages with a gear 20 fast on the central shaft 25, the number of teeth of gear 20 being somewhat different from that of gear 17. Owing to customary "backlash" between gears it is quite practicable to run two gears such as 17 and 20 of substantially the same diameter, but one having one or two teeth more than the other, in mesh with the same pinion or gear (such as 18); and thereby the driven gear (20) is caused to rotate at a speed different from that of the cylinder 1. Shaft 25 extends through roller bearings in a sleeve 22 formed on the inner side of head 4, and is stepped in roller bearings in a sleeve 23 formed on the inner side of the wall of chamber 13. Said sleeves are provided with annular covers.

Within the cylinder 1 are a number of supporting rings 26, and secured to each of said rings is a frusto-conical transversely extending partition 27, 28, 29 and 30. These partitions divide the interior of the cylinder 100 into successive separating chambers or compartments A, B, C and D. The smaller openings of said partitions are larger than the shaft 25, so that around said shaft there is an annular space, through which the material being treated may pass from one compartment to the next. The partitions are preferably set somewhat apart so that the smaller end of each may be opposite the inner wall of the cylinder, whereby material 110 delivered through such smaller openings may reach the inner wall of the cylinder

prior to conveyance into the next conical partition in series. Communicating with the last partition D, is a delivery pipe 31, which extends through the shell of cylinder 1 and opens into a fixed annular delivery chamber 32, in which said cylinder freely turns. On the shaft 25 are arms 33, which carry bars 34, upon which bars are secured conveying scrapers 35. Some of these scrapers act upon the material which is centrifugally deposited on the inner side of the cylinder wall, and others act upon said material deposited on the inner peripheries of the frusto-conical partitions. All of the scrapers are suitably inclined, so as to act as conveyers for said material to carry it from the feed end to the delivery end of the machine.

In the cylinder head 2 is an opening 36 for the escape of liquid into the annular fixed chamber 37. Inserted in the wall of cylinder 1 and protruding into the separating chambers B, C, D, and also into the chamber E (between the partition 30 and the head 4) are open tubes 38. There may also be an opening 39 in the cylinder head 2, near to the center thereof. On the hub of driving pulley 8 is a sprocket wheel 39, which, by means of the chain belt 40, transmits motion to the sprocket wheel 41 on the end of shaft 42 which extends through the bed 7 of the machine and carries, at its farther extremity, a sprocket wheel 43, which, by chain belt 44, rotates sprocket wheel 12. When the driving pulley 8 is rotated the cylinder 1 is caused to turn on its trunnions, thus carrying the pinion 18 in planet movement around the fixed gear 17. Rotary motion is then communicated to pinion 18, which, in turn, imparts it to gear 20, and in this way the shaft 25 is set in rotation to cause the scrapers to be carried around the inner surfaces of the cylinder and conical partitions. The feed conveyor 11 is set in rotation by the sprocket chain 40, actuated by the shaft 42, which, in turn, is driven by the belt 40 from the sprocket wheel 39 on the hub of driving pulley 8.

The operation of the machine is as follows: The combined solid and liquid materials to be separated are introduced into the hopper 9 from the pipe 45, and, thence, by means of the screw conveyor 11, are carried into the chamber 13, whence by the pipe 14 they are delivered into the first separating chamber A. A ring of combined solid and liquid material is formed around that portion of the inner periphery of the cylinder 1, which lies between the first partition 27 and the cylinder head 2. The solids being heavier lie in contact with the cylinder periphery, and the liquid forms a ring inside of said solids. The radial width of this ring cannot, of course, extend beyond the edge of the

liquid escape opening 36, so that as the materials are introduced the liquid thus becomes centrifugally separated from the solids and escapes from the opening 36 in cylinder head 2, and so to chamber 37, and then by outlet 21, (Fig. 3,) from the machine. The solids, with such residual liquid as they may still retain, are carried by the scrapers in chamber A around the inner periphery of the first partition 27 and toward its axis, and are delivered through the central opening in said partition to the second chamber B. Here the centrifugal force again throws the solids out to the cylinder periphery, along and around which they are carried by the scrapers, and so through the partition 28 in chamber C. The same operation is repeated in chamber C, and again in chamber D, and finally the scrapers in chamber D convey the solid material to the outlet pipe 31, through which it is projected by centrifugal force into the fixed chamber 32, from which it is delivered through any suitably disposed opening. Any liquid which may remain in the solid in chamber A, after it is carried by the scrapers to the inner surfaces of partition 27, flows back, and, in fact, is carried back by the centrifugal force to the outlet 36 which is farther away from the axis than such inner surfaces. The solids which are delivered into chamber B contain very little moisture, and, as the interior of chamber B is practically dry, the solids thus become dried through being carried by the conveying scrapers around and along the wall of said chamber and so exposed to the action of the atmosphere. This drying being repeated in chambers C and D, so that when the solids finally emerge at pipe 31, the quantity of moisture left in them is inconsiderable.

As this machine may be advantageously used upon solids and liquids in a heated condition, it is desirable to prevent too high a temperature in the interior of the separating cylinder. To this end, I provide the short tubes 38, which convey atmospheric air into said cylinder, which circulates through the conical partitions to the comparatively large opening 39 in the head 2.

Through the wall of cylinder 1 and in each chamber B, C and D, are made pairs of small openings 46, 47 and 48, which respectively communicate with the annular fixed chambers 49, 50 and 51 each at a point somewhat behind the smaller end of the corresponding frusto-conical partition extending into each such chamber. The purpose of these openings is to permit the escape of any small amount of liquid which may remain in the material while in said chambers, the said liquid then flowing into the annular chambers 49, 50 and 51, from which it is drawn off by any convenient outlet as 24. The openings 46, 47 and 48 are made only

just large enough to allow escape of the liquid. Very little liquid will remain in the solids forced through the smaller end of conical partition 27 and the material thrown 5 against the outer wall of the drum will be practically solid. The material is moreover thrown somewhat in advance of the openings 46, 47 and 48 and within the sweep of the scrapers so that it has no particular tendency to go backward toward the hole. Such wetting liquid as it may still retain on the other hand does flow backward through such solid material, and particularly when the solids begin to move toward the axis in 10 traveling through the coned chamber, and so ultimately reaches the opening. The same action of course occurs in each successive chamber. Any number of frusto-conical partitions may be employed depending 15 on the number of separating chambers A, B, C, etc. desired. The various chambers A, B, C and D and the rotary conveyers therein constitute in effect, it will be seen, separate rotary separators arranged in series; and the 20 apparatus as a whole may be described as a "multiple effect" separator.

I claim:

1. A machine for separating solids from liquids, comprising in combination a plurality of rotary chambers arranged in series and each having an inclined surface leading to an outlet opening, such openings of chambers other than the last leading to the chamber beyond, means for the escape of liquid at the point of greatest diameter in each such chamber and means for sweeping solid material along such inclined surfaces to such openings.

2. A machine for separating solids from liquids, comprising in combination a plurality of rotary chambers arranged in series and each having a cylindrical portion and beyond it an inclined surface leading to an outlet opening, such openings of chambers other than the last leading each to the chamber beyond and located opposite the cylindrical portion of said chamber, so that the discharge from such opening passes to the cylindrical portion of the chamber beyond, and means for sweeping solid material along such inclined surfaces to such openings, each chamber further provided with means for the escape of liquid.

3. A machine for separating solids from liquids, comprising in combination a rotatable chamber having within it a plurality of inclined surfaces arranged in series and leading to discharge openings, said inclined surfaces spaced apart with cylindrical portions of the chamber between them, said discharge openings each located opposite a cylindrical portion of the chamber, so that the discharge from such opening passes to such cylindrical portion of the chamber be-

yond, and means for sweeping solid material along such surfaces to such openings.

4. A machine for separating solids from liquids, comprising in combination a rotary chamber having within it a plurality of coned partitions having discharge openings at their smaller ends, said coned partitions spaced apart, with cylindrical portions of the chamber between them, the opening of one such cone leading to the chamber between that cone and the next, and being opposite a cylindrical portion of such chamber beyond, and means for sweeping solid material up such coned partitions.

5. A machine for separating solids from liquids, comprising in combination a rotary chamber having within it a plurality of coned partitions spaced apart, the said chamber having cylindrical portions between said partitions, said partitions having discharge openings at their smaller ends located opposite cylindrical portions of the sides of the chamber, the opening of one such cone leading to the chamber between that cone and the next, and means for sweeping solid material up such coned partitions, said chamber provided with means for the escape of liquid from the spaces between the partitions.

6. A machine for separating solids from liquids, comprising in combination a rotary drum having within it a series of coned partitions spaced apart, the said chamber having cylindrical portions between said partitions, said partitions having discharge openings at their smaller ends located opposite cylindrical portions of the sides of the drum, a rotary shaft arranged longitudinally, and means thereon for sweeping solid material up said partitions toward said openings.

7. A machine for separating solids from liquids, comprising in combination a rotary drum having within it a series of coned partitions spaced apart, the said chamber having cylindrical portions between said partitions, said partitions having discharge openings at their smaller ends located opposite cylindrical portions of the sides of the drum, a rotary shaft arranged longitudinally, and means thereon for sweeping solid material up said partitions toward said openings, said drum provided with means for the escape of liquid from the chambers between said partitions.

8. In a centrifugal separator, a rotary casing containing a series of chambers arranged to successively receive and treat material, each of said chambers having a cylindrical surface and another surface converging toward the axis and terminating in a discharge opening which, in the case of each chamber but the last, is opposite a cylindrical portion of the chamber beyond, and means for carrying the material forward along such converging surfaces, back to the casing

wall and then again along the converging surfaces.

9. In a centrifugal separator, a rotary casing containing a series of chambers arranged to successively receive and treat material, each of said chambers having a cylindrical surface and another surface converging toward the axis and terminating in a discharge opening which, in the case of each 10 chamber but the last, is opposite a cylindrical portion of the chamber beyond, and means for moving solid material along said surfaces toward said axis and back to the interior wall of the casing at the end of each 15 such surface, said casing provided with means for the escape of separated liquids.

10. A machine for separating solids from liquids comprising in combination a rotary drum having within it a plurality of spaced 20 inclined surfaces arranged in series, there being cylindrical portions of the walls of the drum between said surfaces, each such surface terminating in a discharge opening which, in the case of each chamber but the 25 last, is opposite one of the said cylindrical portions of the walls of the drum, a rotary shaft within said drum, means thereon for sweeping solid material up such inclined surfaces from the drum wall in succession, 30 means for rotating the drum and means for rotating said shaft at a speed different from that of the drum.

11. A machine for separating solids from liquids, comprising in combination a rotary 35 drum having within it a plurality of inclined surfaces arranged in series, a rotary shaft within said drum, means thereon for sweeping solid material up such inclined surfaces, means for rotating the drum, a fixed gear, 40 another gear having a different number of teeth and mounted on said shaft and a pinion carried by the drum and in mesh with both said gears.

12. A machine for separating solids from liquids, comprising in combination a rotary 45 vessel, having a plurality of chambers arranged in series and communicating one with another, wherein solids are centrifugally projected to the sides of such vessel, 50 and, alternating with said chambers, a plurality of devices for conveying said solids centripetally.

13. A machine for separating solids from liquids, comprising in combination a rotary 55 cylindrical vessel having a plurality of frusto-conical partitions arranged in series and spaced apart with cylindrical portions of the walls of said vessel between them, and having discharge openings at their 60 smaller ends opposite the said cylindrical portions of the walls of said vessel intermediate said partitions, and means for conveying the material to be separated alternately over the vessel walls and over the 65 concave peripheral surfaces of said parti-

tions and through the said discharge openings.

14. A machine for separating solids from liquids, comprising in combination a rotary vessel having within it a series of frusto- 70 conical partitions spaced apart with cylindrical portions of the walls of said vessel between them and having discharge openings, at their smaller ends opposite the said cylindrical portions of the walls of said vessel intermediate said partitions and dividing the vessel into a plurality of chambers, means for the escape of liquid from said chamber, means for feeding combined solid and liquid material into the first chamber, 75 means for conveying solid material along said vessel wall and along said partitions to the discharge openings therein, and means for discharging solids from the last chamber. 80

15. A machine for separating solids from 85 liquids, comprising in combination an approximately horizontal rotary cylinder, a plurality of coned partitions arranged in series and spaced apart with cylindrical portions of the walls of said cylinder between 90 them and having discharge openings at their smaller ends opposite the said cylindrical portions of the walls of said cylinder intermediate said partitions, means for sweeping solid material up said partitions to said 95 discharge openings, means for the escape of liquid from said cylinder, and a feed duct discharging into said cylinder and a conveyor therein.

16. In a machine for centrifugally separating solids from liquids, a rotary cylindrical vessel comprising a plurality of chambers separated by fixed transversely extending partitions wherein mixed solids and liquids undergo successive separations, said 100 vessel having means for the escape of centrifugally ejected liquid and means for feeding solid material through the chambers 105 successively.

17. A centrifugal machine comprising a 110 plurality of connected coned rotary chambers, each such chamber having imperforate curved surfaces extending from near the periphery inward and provided with openings for the discharge of solid material from the 115 one chamber to the next said opening in the one nearly coinciding with the beginning of the next in order, and means within said chambers for feeding solid material forward from near the peripheries over such imperforate surfaces toward such openings, said 120 chambers being provided with means for the escape of separated liquid at their points of greatest diameter.

18. A centrifugal machine comprising in 125 combination a plurality of rotary communicating open ended chambers, each having inwardly inclined imperforate surfaces at one such open end leading to an opening of relatively small diameter, means for feeding 130

a mixture of solid and liquid material to one of said chambers, and means for feeding solid material from near the peripheries of said chambers over said inclined imperforate surfaces toward the said openings, said chambers provided with means for the escape of separated liquid at their point of greatest diameter, and the last chamber provided with means for the discharge of separated solid material.

19. A centrifugal separator comprising in combination a rotary drum having means for delivering therein a mixture of solid and liquid materials, and means for moving the solid material from near the periphery of said drum toward the axis of the drum, returning it again to near the periphery, and again moving it toward the said axis, said drum provided with means for the escape of separated liquid at its periphery.

20. A centrifugal separator comprising in combination a rotary drum having within it one or more partitions extending from near the periphery toward the center, and each provided at a point distant from the periphery with a discharge opening, means for de-

livering a mixture of solid and liquid materials into said drum, and means for moving solid material to such discharge opening or openings, said drum provided with means for air circulation comprising air conduits extending from the outside of the drum inward to a point beyond the normal level of material against the periphery.

21. A centrifugal separator comprising in combination a drum rotatable about a central axis, one or more transversely extending coned partitions within said drum each having an opening near the center, a conveyer shaft having its axis coincident with the axis of rotation and provided with conveying means, means for rotating said shaft and means for the supply of mixed solid and liquid materials and for the escape of separated liquids and solids.

In testimony whereof I have signed my name to this specification in the presence of two subscribing witnesses.
